ABSTRACT: Fuel additives that substantially improve the combustion characteristics and economy of combustible fuels when present in trace quantities are disclosed. The new additives include inorganic zirconium compounds and organic amines.

ADDITIVES FOR COMBUSTIBLE FUELS

BACKGROUND OF THE INVENTION

The invention relates to both inorganic metallic and organic amine additives for combustible fuels. More specifically, the invention is concerned with fuel additives that significantly increase fuel economy as well as resulting in more complete combustion and higher flame temperatures. In addition, the new additives typically act as corrosion and sulfation inhibitors in a fuel mixture, thereby performing a detergent function as well as improving the combustion process.

The fuel additives in accordance with the invention are particularly effective when used with liquid hydrocarbon fuels, such as fuel oils, kerosene, gasoline, etc. Advantageous results may be obtained by using the additives of the invention with solid fuels such as coal and gases, including oxygen, acetylene, hydrogen, natural and coal gases. The new additives have also been found effective for use in petroleum refining and refractories.

A considerable variety of substances, such as manganese dioxide, for example, have been heretofore used as additives for improving the combustion and economy of fuels. However, the improvement in fuel economy obtainable with known additives has been very moderate and, typically, obtainable only with undesirable side effects such as unburnable deposits and corrosion.

The invention provides fuel additives that provide a significant improvement in combustion characteristics of combustible fuels without the typical undesirable side effects. Further, the new additives are very inexpensive and are used in very small (trace) quantities.

SUMMARY OF THE INVENTION

The present invention is based on the discovery that certain inexpensive inorganic metallic compounds and organic amine compounds result in substantial increases in fuel economy when added to combustible fuels in trace quantities.

In accordance with the invention, inorganic compounds of the metal zirconium, including the potassium, sodium, and lithium salts when present in trace quantities in a fuel mixture can increase fuel economy from about 5 to 20 percent, or more.

In accordance with a specific aspect of the invention, it has been discovered that potassium fluorozirconate compounds of the formula (K_2ZrF_y) where y is 10 or less, and particularly the penta- and hexafluorozirconates (wherein y is 5 or 6) have been found to be remarkably effective additives for hydrocarbon and other fuels.

Additionally, it has been discovered that the organic amine N,N,N',N' -tetramethyl-1,3-butanediamine is a very effective fuel additive, providing hydrocarbon and other fuels with improved combustion and greater economy as well as helping to keep ignition and combustion surfaces clean. Typically, from 0.5 to 2 cc. of the N,N,N',N' -tetramethyl-1,3-butanediamine additive is used per 10 gallons of fuel.

While the inorganic zirconium metal compounds of the invention appear to perform as a catalyst for the combustion process, i.e., they are not consumed during combustion and can be used in a physical form not miscible with the fuel; the organic amine additives are consumed during combustion and should be added to the fuel in a form that is miscible with the fuel. Since the organic amine additives of the invention are not typically soluble in liquid hydrocarbon fuels, they are advantageously first mixed with a solvent such as alcohol before being added to the fuel.

In accordance with the invention, the new inorganic zirconium metal and organic amine fuel additives can be utilized either independently or together in a fuel mixture for advantageous fuel economy results.

DESCRIPTION OF PREFERRED EMBODIMENTS

The new and improved inorganic zirconium fuel additives can be used in solid form or in an aqueous solution, depending

on the specific application. Potassium hexafluorozirconate has excellent water solubility, without recrystallization when dissolved in boiling water at about a 3 percent by weight concentration. However, since the new zirconium additives typically function as a catalyst for hydrocarbon fuels, it is not essential to use them in solution or for them to be soluble with the fuel.

In the form of an aqueous solution (3 percent by weight K_2ZrF_6) the new zirconium additives can be injected directly into the combustion chamber of a furnace burning a hydrocarbon fuel. When so injected, the 3 percent by weight solution can be diluted to an active ingredient concentration of 1/10 of 1 percent by weight.

The aqueous solution form of the new zirconium additives can also be used to improve the fuel economy of coal by directly spraying the aqueous solution over the coal. Alternatively, the solid zirconium additives of the invention may be blended with powdered solid coal.

The optimum quantity of zirconium compound additive according to the invention is approximately $\frac{1}{2}$ to 1 gram per 18 to 20 gallons of liquid fuel. For solid fuels such as coal, an equivalent amount of the zirconium additive based on the relative heat value for the solid fuels, should be utilized. For all fuels, generally, an equivalent amount of additive should be used per equivalent B.t.u. value of the fuel.

The following examples are supplied to illustrate the advantageous results obtainable by applying the principles of the invention.

EXAMPLE 1

About $\frac{1}{2}$ to 1 gram of potassium hexafluorozirconate was placed in an ordinary household gas burner so that the natural gas (as supplied by the public utilities company) contacted the zirconium compound immediately before combustion.

Eight ounces of water was heated to a boil on the gas burner both with and without the zirconium compound in place.

It was observed that the water consistently reached its boiling point in 12 percent less time when the natural gas contacted the zirconium compound in the burner prior to combustion.

EXAMPLE 2

Oil burner tests utilizing trace amounts of potassium hexafluorozirconate with number 2 and number 4 fuel oil have resulted in a substantial increase in burner temperature. The amount of fuel consumed in trials wherein the zirconium compounds was present and absent was the same since the nozzle used was consistently the same. Further, the air, fuel ratio was maintained at a constant value between trial runs with and without the zirconium additive. For the oil burner tests, potassium hexafluorozirconate was added to the oil supply tank in amounts ranging from about one-half to 1 gram per 20 gallons of fuel.

The results of these oil burner tests have shown that, with all the other variables being equal, the burner temperature is consistently from between 5 and 12 percent higher when trace amounts of potassium hexafluorozirconate are present in the fuel mixture than when the zirconium compound additive is absent. Consequently, a lesser amount of fuel would be consumed to produce a given number of B.t.u.'s when trace amounts of the zirconium additives are present in the fuel oil tank.

EXAMPLE 3

An equal part by volume mixture of N, N, N', N' -tetramethyl-1,3-butanediamine and 200-proof ethanol was prepared. Two cubic centimeters of the mixture was added per 10 gallons of gasoline. A Volkswagen sedan, when run under highway conditions at a constant 50 m.p.h., was observed to provide a fuel economy of 40 miles per gallon of fuel mixture. The same automobile, when operated under the same conditions using the same gasoline without the amine additive of the invention, was consistently observed to have a fuel consumption rate of 27 miles per gallon.

In accordance with the invention, the new and improved inorganic zirconium compound fuel additives may be utilized with compressed gases such as oxygen, acetylene, and hydrogen, and other gases. In gaseous applications, a trace quantity of the zirconium compound can be placed within the tank of compressed gas such that when the gas is released it passes over the zirconium compound.

In petroleum-refining applications, the new and improved fuel additives can be mixed with the refractory material, e.g., porcelain, asbestos, coral, or any other suitable material, before it is placed in the refining tower.

Although the actual mechanism by which the zirconium additives of the invention enhance fuel economy is not presently known, it has been observed that the inorganic zirconium additives are not consumed in the fuel combustion process and apparently act as a catalytic agent in the combustion process. It is believed that the new zirconium additives cause atomic and/or molecular changes in fuels they contact, resulting in the generation of more heat per unit of fuel and therefore requiring the consumption of less fuel for the generation of a given amount of heat.

Since the new zirconium fuel additives of the invention are used in trace quantities and are not consumed in the combustion process, their use is extremely economical and justifiable in practically any application utilizing a combustible fuel. Although, at present, potassium hexafluorozirconate (K_2ZrF_6) has been found to be the most economical of the new zirconium metal additives, potassium pentafluorozirconate (K_2ZrF_5), although substantially more expensive than the hexafluoro compound, should give comparable fuel economy results.

It should be understood, of course, that the specific examples described herein are intended to be representative only, as certain changes may be made therein without departing from the clear teachings of the disclosure. Accordingly, reference should be made to the following appended claims in determining the full scope of the invention.

I claim:

1. The composition comprising a combustible solid or liquid hydrocarbon fuel and an effective trace amount of an additive to increase fuel economy selected from the group consisting of K_2ZrF_5 and K_2ZrF_6 .
2. The composition of claim 1 wherein said fuel is a fuel oil.
3. The composition of claim 1 wherein said fuel is a liquid hydrocarbon fuel, said additive is K_2ZrF_6 and said amount is about $\frac{1}{2}$ to 1 g. of additive per 18-20 gallons of fuel.
4. The process of increasing the fuel economy of combustible hydrocarbon fuels which comprise contacting said fuel with an effective trace amount of an additive selected from the group consisting of K_2ZrF_5 and K_2ZrF_6 and burning said fuel in contact with said additive, which acts as a catalyst.
5. The process of the claim 4 wherein said fuel is a natural gas and said additive is K_2ZrF_6 .
6. The composition comprising a combustible liquid hydrocarbon fuel and an effective trace amount of N,N,N',N'-tetramethyl-1,3-butanediamine to increase fuel economy.
7. The composition of claim 6 wherein said fuel is gasoline and said amount is from about 0.5 cc. to about 2 cc. per 10 gallons of fuel.
